UNITED STATES PATENT OFFICE.

JOSEPH KUCZKOWSKI, OF BAY CITY, MICHIGAN.

DOOR LATCH.

1,417,391.

Specification of Letters Patent. Patented May 23, 1922.

Application filed April 7, 1921. Serial No. 459,222.

To all whom it may concern:

Be it known that I, JOSEPH KUCZKOWSKI, a citizen of the United States of America, residing at Bay City, in the county of Bay and State of Michigan, have invented certain new and useful Improvements in Door Latches, of which the following is a specification.

This invention relates to latches and the like.

One object of the invention is to provide a simple and convenient latch which will be applicable to doors of any description.

A further object is to design a strong and durable latch which will be composed of relatively few parts, all of which can be metal stampings.

A still further object is to provide an inexpensive latch for use on automobile doors and the like, which can also be locked when desired.

With the above and other objects in view, the present invention consists in the combination and arrangement of parts, herein after more fully described, illustrated in the accompanying drawings, and particularly pointed out in the appended claims, it being understood that changes may be made in the form, size, proportion and minor details of construction without departing from the spirit or sacrificing any of the advantages of the invention.

In the drawings:

Fig. 1 is a front view of my improved latch showing it in locked position.

Fig. 3 is a view similar to Fig. 1 showing it in unlocked position.

Fig. 2 is a cross sectional view taken on the line 3—3 of Fig. 1.

Fig. 4 is an enlarged fragmentary detail showing the operating rod in two different positions.

Fig. 5 is an edge view of the knob.

Fig. 6 is a bottom view thereof.

Fig. 7 is an enlarged cross sectional end view showing the locking member.

Fig. 8 is a side view thereof.

Fig. 9 is a fragmentary top plan view of the conventional automobile door showing my improved lock in position thereon, and

Fig. 10 is a side view thereof.

Referring now particularly to the drawing in which I have provided a sheet metal case 1 for housing the locking mechanism, this case is provided with a cover 2 adapted to be secured thereon, and also to the door in

which the latch is placed by means of screws 3 extending through the openings 4 formed in the flanged portions of the latch casing, an opening 5 being provided in the edge of the case, and also in the cover to allow for the reception of a staple or other similar projection 6 carried by the door frame, and which can be rigidly secured thereto in any desired manner, but in this instance I have shown the staple cast integral with a plate 7 which is attached to the door frame by means of screws or the like.

A preferably sheet metal bracket or stamping 8 is positioned in this case 1 being formed as shown, the lower edge being bent at right angles to the main body, the ends 9 being bent upwardly and are adapted to be secured to the side walls of the case by means of rivets or the like, the main body of this bracket 8 extends upwardly terminating in a pair of forked extremities 10 and 11 as shown, an arcuate stamping member 12 being pivotally attached to the extremity 11 at the point 13 one end of this said member being yieldably connected to the lower edge of the member 8 by means of the spring 14. A latch member 15 is pivotally connected to the opposite extremity at the point 16, a lip 17 being formed integral therewith and extends laterally from this member 15, a similar lip 18 being provided on the member 12, and a compression spring 19 is interposed between and secured to these lips as shown, and it will be obvious that this spring will exert a force tending to maintain the latch in the locked position as shown in Fig. 1 at all times. The end 20 of the point 10 is also bent at right angles to the main body and serves as a clasp which the latch 15 engages when in locked position.

A flat lever 21 is pivoted intermediate its length to the member 8 at the point 22, rods 23 and 23^a being pivotally connected thereto as shown, these rods extend through suitable openings provided in the casing, the free ends thereof being threaded to receive the knobs 24 which are internally threaded for engagement therewith. A coiled spring 25 surrounds the rod 23 one end thereof being anchored to the casing 1 while the opposite end is secured to the rod 23 intermediate its length, and it will be apparent that when pressure is exerted on either one of the knobs 24 that the spring 25 will be stretched, the lever 21 will rock on its pivot 22 and the end of the rod 23 will engage the bent lip

26 of the latch 15 swinging it on its pivot 16 and disengaging it from the projection 10, when it will assume the position as shown in Fig. 3 of the drawings, leaving the door free 5 to open, and when the door is closed the member 6 engages the inner end of the member 12 forcing it downwardly and the latch 15 into locked position, and it will be understood that the door will be unlocked by applying pressure on either knob.

When this latch is used on automobiles of the closed type it is sometimes preferable to have a locking attachment so that one or both doors can be locked from the inside of the car, one of the doors having a lock and key, and with this in view I have provided the curved locking member 27 pivoted to the door by means of a screw or the like and adapted to fit a slot provided in the member 23^a, the end of this member 27 being bent as shown at 27^a to provide a finger hold for proper manipulation thereof.

While I have shown the latch as applied to an automobile door it will be readily understood that it can be used on any door or piece of mechanism which requires that it be opened and closed.

From the foregoing description it will be obvious that I have perfected a simple and efficient latching mechanism of durable construction which can be operated from either side of the door by the application of pressure to either of the knobs.

What I claim is:—

35 1. A door latch comprising a case, a bracket rigidly mounted in the said case and having laterally extending forked extremities, a substantially arcuate member pivoted to one of said extremities, a latch member 40 pivoted at the outer end of said member, the inner end being yieldably connected to the bracket, and a spring member anchored to the said arcuate member and the said latch for normally forcing it into engagement 45 with the other bracket extremity, and means for releasing the said latching mechanism.

2. A door latch comprising a bracket having laterally extending forked extremities, a substantially arcuate member pivoted to one of said extremities and a latch pivoted to the upper end thereof, resilient means connecting the lower end of the arcuate

member to the base of the bracket, and an expansion spring anchored to the arcuate member and latch respectively for normally forcing the latch into engagement with the opposite extremity of the bracket, a lever pivoted to the bracket and operating rods connected thereto, the end of one rod engaging the said latch for unlatching it, and means for normally holding said rod out of engaging with the said latch.

3. A door latch comprising a case having a bracket rigidly mounted therein and provided with laterally extending forked extremities, an arcuate member pivotally mounted on one extremity and a latch pivotally mounted on the said arcuate member, resilient means for connecting the lower end of the arcuate member to the base, and an expansion spring anchored to the latch and arcuate member respectively for normally holding the latch into engagement with the opposite extremity of the bracket, a lever pivoted to the bracket and operating rods 75 pivotally connected to the ends thereof, one of said rods being adopted to engage said latch when pressure is applied to the free end of either rod, means for normally holding said rod out of engagement therewith, and means for locking the rod against movement.

4. A door latch comprising a case having a bracket rigidly mounted therein, and having laterally extending forked extremities, a substantially curved member pivoted to one of said extremities and a latch carried thereby, the lower end of the curved member being resiliently connected to the base of the bracket, and a spring anchored to the curved member 90 and latch respectively for holding said latch in engagement with the opposite extremity of the bracket, a lever pivoted intermediate its length to the bracket and handles secured to the ends thereof, the end of one of the 95 rods engaging the latch when pressure is applied to either rod, resilient means for holding said rod from engagement with the latch, and a staple adapted to contact with the lower end of the curved member 100 when the door is closed for swinging the latch into engagement with the bracket.

In testimony whereof I affix my signature.
JOSEPH KUCZKOWSKI.
